UNITED STATES PATENT OFFICE.

GUSTAF M. ANDERSON, OF WATERLOO, IOWA.

ADJUSTABLE CREAM-EXIT FOR CENTRIFUGAL CREAM-SEPARATORS.

1,016,536.

Specification of Letters Patent.

Patented Feb. 6, 1912.

Original application filed June 16, 1909, Serial No. 502,505. Divided and this application filed April 17, 1911. Serial No. 621,518.

To all whom it may concern:

Be it known that I, GUSTAF M. ANDERSON, a citizen of the United States of America, and a resident of Waterloo, Black-hawk county, Iowa, have invented certain new and useful Improvements in Adjustable Cream-Exits for Centrifugal Cream-Separators, of which the following is a specification.

10 My invention relates to improvements in centrifugal cream separators, and the object of my improvement is to provide for the bowl of such a separator a regulable non-clogging cream-exit, formed of communicating channels of different radial widths with the inner wall of the entrance channel approaching more nearly the axis of the bowl than the nearest part of the inner wall of the other or exit channel, a movable dam being 15 furnished to intercept adjustably the communication of said channels and lying partly within the interior hollow of each channel. This object I have accomplished by the means which are hereinafter described and 20 claimed, and which are illustrated in the following drawings.

This application is a division of application Serial Number 502,505, filed by me on June 16th, 1909.

30 In the drawings: Figure 1 is a central vertical axial section of the bowl of a centrifugal cream separator, showing in central vertical section my improved regulable non-clogging cream-exit device. Fig. 2 is an 35 upper plan view of the cream-exit head and a broken portion of the diaphragm on which it is mounted. Fig. 3 is a vertical central section of the structures shown in Fig. 2, taken through the axis of the communicating 40 channels leading to the cream-exit. Fig. 4 is a side elevation of the structure shown in Fig. 2. Fig. 5 is an enlarged detail diagrammatic view of the communicating 45 adjustable dam, parts being shown broken away and the radially-varying density of the separated cream indicated therein by dotted shading.

The bowl of the separator shown is in 50 two portions, the body 11 and a removable base 15, the spindle 14 being axially united to the latter. The contacting parts of the

body 11 and the base 15 are provided at their line of junction with a rubber gasket 16 set in an annular groove in the base to prevent 55 leakage. The upper end of the spindle projects above the base 15 in the form of a boss which is fitted within the hollow lower end of a milk inlet-tube 1, but is grooved to afford channels which communicate with the 60 radially-directed milk delivery orifices 13. The tube 1 is integral with said base and concentric with the axis of the bowl. When said base and tube have been fitted within said bowl, a lock-nut 2 serves to secure the 65 upper end of the tube in its seat in the contracted top of the bowl. A frustum-supporter 8, in the form of a hollow cylinder, is removably fitted over the inlet-tube 1, and is provided on its exterior surface with a 70 plurality of spaced apart low vertical ridges. The lower end of the cylinder 8 is secured to and communicates with a concentric hollow frustum 24, whose upper edges are bent inwardly to approach the cylinder horizontally, while the horizontal portion is provided with a plurality of slots 12. The lower part of the frustum 24 is supported on the base of the bowl and is fitted closely but removably about a raised portion thereof. 75

The liner of the bowl is composed of a pile of separating plates each in the form of a hollow frustum 9, with their inner portions bent to extend horizontally inwardly toward the axis of the bowl. The inner edges of 80 said frusta are formed with projections separated by spaces 12, the latter coincident with and lying vertically above the like slots in the frustum 24 so as to register therewith and thus afford uninterrupted channels for 85 the passage therethrough of milk and cream. The ridges on the cylinder 8 keep the frusta 9 in the same registering vertical alinement.

The numeral 23 designates a hollow inner cone within and spaced away from the conical head of the bowl 11, and having a hollow upwardly directed cylindrical extension having a thimble 26 fitted therein. The skimmed milk passes between the cone 23 and the bowl-head into the milk-exit 27. 100 The cream passes upward inside of the cone 23 and into a tubular channel which is formed of two parts, the entrance part 7 in the tube 17 being of larger area with its

inner wall extending nearer to the axis of the bowl than the inner wall of the communicating part 6 in the tube 18. The upper part of the channel 6 is bent or curved outwardly at 4 forming a cream-exit. A screw 5 is fitted within an interiorly-threaded seat at the junction of the channels 6 and 7, so that when it is turned it moves inwardly to partially intercept both channels at their line of communication, the diameter of the screw being slightly larger than the width of the said communication between the two channels.

Referring particularly to Fig. 5, which is a diagrammatical representation of the probable action of my improved variable cream-exit or outlet, it will be seen that it depicts the cream-screw or adjustable dam 5 as partly moved inward toward the axis of the bowl within the outlet at the line of junction of the channels 6 and 7. In this position it so restricts the outer portion of the outlet as to prevent the issue of the most diluted or outer stratum of the cream. For purposes of convenience, I have represented the cream in the channel 7 as divided into three strata, *a*, *b* and *c*, of specific gravities increasing from *a* to *c*. It is, of course, obvious that there are no such exact divisions between strata for the cream varies imperceptibly in its density radially outward from the bowl's axis under the influence of centrifugal force, but as an illustration the definition of strata is convenient. The function, therefore, of the screw 5 is to more or less dam the issuing cream to correspondingly vary its amount of dilution with milk, since if the screw be not intruded into the current of the stratum, *c*, the skimmed cream will have a maximum of dilution with the milk yet unseparated therefrom in the outer zone of the cream wall corresponding with this stratum. If moved radially inward to intercept the stratum *c*, the skimmed cream will be of less specific gravity including the strata *b* and *c*, but if the dam be brought inwardly still more, only the cream of lightest specific gravity in the stratum *a* will be skimmed. Now, the object of my improvement in making the cream outlet communicating channels 6 and 7 of different areas with the inner wall of the channel 7 nearer the axis of the bowl, is this; to afford a greater clearance for the issuing cream to prevent clotting of the cream therein when cold or when exceptionally rich. Even in the event that when cold some of the richest cream may clot upon the inner walls of the passage 7, its area is sufficient to permit a free flow of the cream from the cream zone through the outlet to always be regulable by the screw or movable dam 5 to vary the dilution of said cream as desired. The location of the screw 5 at the junction or com-

munication of the channels 6 and 7 affords a perfect control of the communication, the inner end of the screw being movable partly in the upper end of the channel 7 as well as partly in the lower end of the channel 6 of lesser area. The wider channel 7 also permits of the recession of the cream zone inward toward the bowl's axis farther than in some liners, thereby permitting a surer control of the issuing cream, by giving better clearance to the thickest part of the cream. While the outer limit of the inner walls of both the channels 6 and 7 is the same, the widening of the channel 7 permits of a radially wider cream zone being skimmed, which gives the operator a wider choice of regulation of the dilution of the cream in skimming.

Having described my invention, what I claim as new, and desire to secure by Letters Patent, is:

1. In a cream outlet for a separator bowl, the combination of two channels for the issuing cream, of which one channel is wider radially than the other from the axis of the bowl, and a movable dam located partly in the large and partly in the small channel adapted to variably cut off the flow of cream at the communicating parts of said channels.

2. In a cream outlet for a separator bowl, the combination of two channels for the issuing cream, of which the entrance channel is wider than the other channel in a plane extending radially from the axis of the bowl, and said entrance channel emptying into the other channel, and a movable dam located partly in the wider and partly in the narrower channel adapted to variably control the dilution of the cream passing thereby.

3. In a cream outlet for a separator bowl, the combination of two communicating channels for the issuing cream of which the inner or entrance channel is the wider radially from the axis of the bowl, the outer limits of the inner walls of both being the same but the inner limit of the entrance or larger channel approaching more closely the axis of the bowl than the inner limit of the other channel, and a movable dam located partly within the larger and within the smaller channel at their place of communication.

4. In a centrifugal cream separator bowl provided with an inlet for the full milk and an outlet for the skimmed milk, an adjustable outlet for the separated cream, consisting of a tube in said bowl with its open inner end in communication with the cream zone from the inner limit of the latter outwardly, said tube having a contracted portion with its open end delivering through the bowl and the contracted portion having its inner wall which is nearest the axis of

the bowl spaced away from the said inner-most limit of the cream zone, said bowl having an orifice in communication with the said tube at the place of contraction, and a 5 radially-movable plug within said orifice adapted to vary the width of the latter radially at the place of its contraction.

Signed at Waterloo, Iowa, this 30th day of March, 1911.

GUSTAF M. ANDERSON.
